UNITED STATES PATENT OFFICE.

GEORGE J. MEUER, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRICAL CONNECTER.

Application filed February 21, 1920. Serial No. 360,357.

This invention relates to electrical connectors and more particularly to cord connectors, although certain features thereof are also generally applicable to separable devices having co-operating contacts to be engaged and disengaged by substantially rectilinear movements.

In devices of such character the co-operating contacts are usually designed to interlock and it is therefore important that they be insured engagement in a given relation. On the other hand, the necessity of precise relative positioning of the contacts prior to engagement thereof is annoying and the present invention has among its objects to provide an improved device of simple construction wherein the contacts will be insured engagement in the proper relation and wherein provision is made for considerable latitude in relative positioning of the contacts prior to engagement thereof.

Another object is to provide a device of the aforesaid character having improved contacts so mounted as to facilitate interlocking thereof and to better fulfill their electrical and mechanical functions.

Another object is to provide a device of the aforesaid character comprising a minimum number of simple and rugged parts compactly but yet conveniently arranged.

Another object is to provide a device of the aforesaid character having simplified and improved means for relieving strain upon the conductor terminals.

Other objects and advantages will herein-after appear.

In the accompanying drawing, wherein is illustrated an embodiment of the invention,

Figure 1 is a longitudinal sectional view thereof;

Fig. 2 is a similar view but in a plane shifted angularly through approximately ninety degrees;

Fig. 3 is a horizontal illustration substantially on line 3—5 of Fig. 1, as viewed from above;

Fig. 4 is a similar illustration substantially on line 4—4 of Fig. 1 as viewed from above;

Fig. 5 is a horizontal illustration also substantially on line 3—5 of Fig. 1 but viewed from beneath and showing the conductors attached; and

Fig. 6 is an enlarged transverse sectional

view showing one pair of the cooperating contacts in interlocked relation.

Referring to the drawing, the same illustrates a cord connector comprising a cylindrical central member 6 of insulating material and substantially hemispherical end members 7 and 8 also of insulating material, the end member 8 being in practice permanently secured to said central member to provide a receptacle for contacts carried by the end member 7 which is separable from the other members.

End members 7 and 8 are respectively provided with axial conductor passages 9 and 10 and with projecting co-operating pairs of spaced contacts 11, 11 and 12, 12 while the member 6 is provided with through passages 13 each to receive a pair of oppositely extending contacts 11 and 12. The two pairs of contacts render the connector of a double pole character and when the contacts are engaged they interlock to releasably secure the end member 7 to the member 6.

More specifically, said contacts are arranged to lie substantially parallel with and to overlap one another upon diametrically opposite sides of the respective conductor passages 9 and 10, the contacts 11 being spaced a relatively greater distance to fit outside the corresponding contacts 12. The outer surfaces of contacts 12 are provided respectively with humps adapted to take into corresponding indentations of the inner surfaces of respective contacts 11 for locking the members against accidental separation and also against relative rotation. The tips of contacts 11 are tapered and flared outwardly whereas the tips of contacts 12 are flared inwardly to assist in guiding the same into suitable interlocking relation during telescoping thereof.

Said contacts are provided with rectangularly bent substantially flat base portions 14, 14 and 15, 15 for securement thereof to the respective members of the connector. The projecting portions of the contacts 11, which in service are frequently exposed, are transversely arched and such arching continues through the bend between said base and projecting portions for imparting strength and rigidity to the latter particularly at the line of such bending, while for

a like purpose these members are constructed appreciably wider than the members 12 and of heavier stock. The projecting portions of said members 12 beyond their lines 5 of bending are similarly arched to fit accurately within the members 11, such joint arching also assisting in positioning of said contacts.

The passages 13 are of substantially uniform segment-shape in cross section being extended radially of the member 6 a distance appreciably greater than the combined thickness of either pair of co-operating contacts to provide space for radial yielding 10 of said contacts relative to one another during telescoping thereof. Moreover, each of said passages is formed relatively broad upon its side toward the periphery of said member 6 to receive one of the broad contacts 11, while the walls of said passage converge laterally toward the respective narrow contacts 12 to provide against insertion of the contacts 11 in a relation too close 15 to the axis of the device to co-operate properly with said contacts 12. Said openings being thus materially larger than the contacts to be inserted therein, are adapted, in conjunction with the tapered tips of said contacts, to facilitate entry of the latter within 20 the former, assuming only approximately accurate prior positioning thereof, whereas the peculiar shape of said passage serves during full insertion of said contacts to guide the same into suitable relation with respect 25 to the contacts 12.

The base portions of the several contacting members are adapted to fit snugly within correspondingly shaped recesses in the adjacent flat surfaces of end members 7 and 40 8, the latter having each a pair of shouldered and internally screw-threaded metallic inserts 16 formed therein and projecting a short distance axially within the respective recesses and through suitable openings in 45 the respective base portions of said contacting members, being riveted therebeyond. Each of base portions 14 and 15 is of reduced width between its point of securement and the root of its projecting contact, such 50 reduced portions providing for resilient radial yielding of said contacts. Terminal screws 17 are carried within said inserts whereby the latter serve for securement both of the contacting members and the conductors therefor, whereas the sides of the recesses serve to prevent lateral movement 55 or swinging of said contact members.

The base portions of the contacting members 12 are further provided with offset lugs 60 18 arranged substantially flush with the flat surface of the end member 8. Said lugs are provided with screw threaded openings adapted to receive screws 19 extending through counterbored openings in the center member 6 for securing said center and end

members together as described, while permitting separation thereof for wiring.

Each of said end members 7 and 8 is provided with a device for relieving strain upon the conductor terminals thereof, such devices comprising flat bridge members 20 arranged flatwise in the respective conductor passages 9 and 10 and substantially bisecting the same. Each of said bridge members is provided with a portion 21 extending within such conductor opening and with shouldered terminal portions 22 adapted to fit within suitably arranged slots 23 which communicate both with the flat surface and with the conductor passage of their respective end member and having corresponding shoulders for accurate positioning of said bridge member with its exposed edge 24 substantially flush with such flat surface. Said exposed edge 24 is provided with an extended notch 25 having its base substantially in the radial plane of the adjacent conductor terminals.

In wiring either of said end members, the conductor is passed inwardly through the conductor opening, with one of its wires upon either side of the bridge member, said wires being bent across the latter and within the notch 25 thereof for connection with the opposite terminal screw. The bridge thus provides substantially a right angle bend of the conductor wires whereby any pull upon the conductor is taken by the bridge and not by the terminals. The location of the wires within the notches 25 also provides against radial displacement of the former. The center member 6 may furthermore be recessed as illustrated at 26 to provide additional space for the wires as the same pass the bridge and to further provide against lateral shifting of said wires.

What I claim as new and desire to secure by Letters Patent is:

1. In combination, cooperating members provided with contacts to be engaged and disengaged by substantially rectilinear movement, the contacts of one of said members projecting therebeyond and the contacts of the other member being relatively narrower and confined in substantially V-shaped passages therein, said last mentioned contacts being located adjacent to the converging point of the walls of said passages, and said other contacts being admissible into said passages only at a predetermined distance from said converging point to thereby insure proper engagement of the respective contacts.

2. In combination, cooperating members provided with contacts to be engaged and disengaged by substantially rectilinear movement, the contacts of one of said members projecting outwardly therefrom, and the contacts of the other member being narrower than said projecting contacts and

confined in passages in said member, each of said passages being of substantially uniform cross section throughout its length and having its walls converging toward the contact confined therewith.

3. The combination with a pair of insulating members, a plurality of outwardly projecting cooperating contacts carried by said members, the contacts on one of said members being of greater width than the contacts on the other member, an insulating member secured to said last mentioned member and having passages therethrough of substantially V-shape in cross section, said last mentioned contacts being located adjacent the respective points of convergence of the walls of said V-shaped passages, and the other contacts being movable into said passages only at a greater distance from said points of convergence.

4. A quick detachable-cord connector comprising a plurality of insulating members, one of said members carrying a plurality of contacts and another of said members carrying a plurality of smaller contacts adapted to cooperate therewith, all of said contacts being of substantially concavo-convex form in cross section, the convex surfaces of said small contacts being adapted for engagement with the concave surfaces of the other contacts, a third insulating member secured to said second mentioned member and having substantially V-shaped through passages of uniform cross sectional area to receive said small contacts adjacent the respective points of convergence of the walls thereof, said large contacts being admissible into said passages only in a relation to engage the convex surfaces of the other contacts, and means for releasably interlocking said contacts when in engagement.

5. In combination, co-operating members provided with contacts adapted to be engaged and disengaged by substantially rectilinear relative movement, one of said members having its contacts projecting therebeyond and the other member having contacts of less width yieldingly confined in passages therein, said passages being materially larger than said projecting contacts to facilitate entry of the latter within the former and each of said passages having its walls converging laterally toward the contacts contained therein to provide for a given relation of said co-operating contacts when engaged, said co-operating contacts being shaped with respect to each other in a manner to assist in relative positioning thereof.

6. In combination, co-operating members provided with contacts adapted to be engaged and disengaged by substantially rectilinear relative movement, one of said members having its contacts projecting therebeyond and the other member having narrower contacts confined within passages therein,

said co-operating contacts having releasable interlocking means and complementary guiding means to assist in accurate relative positioning thereof, said passages being materially larger than said projecting contacts to facilitate insertion of the latter within the former and each of said openings having its walls converging laterally toward the contacts confined therein for insuring insertion of said projecting contacts only in such relation as to render said guiding means effective.

7. In combination, co-operating members provided with contacts adapted to be engaged and disengaged by substantially rectilinear relative movement, one of said members having its contacts projecting therebeyond and the other member having relatively narrower contacts yieldingly confined in passages therein, said passages having free openings materially larger than said projecting contacts to facilitate entry of the latter within the former and having walls converging laterally toward the contacts confined therein for insuring engagement of said co-operating contacts only in a given relation and also having wall portions spaced laterally from in-bent portions of said confined contacts to permit yielding thereof during insertion of said projecting contacts.

8. In combination, co-operating members provided with contacts adapted to be engaged and disengaged by substantially rectilinear relative movement, one of said members having its contacts projecting therebeyond and the other member having contacts of less width yieldingly confined in passages therein, said passages having free openings and being materially larger than said projecting contacts to facilitate entry of the latter within the former and being of tapered form in transverse section to permit full insertion of said contacts only in a given relation to said confined contacts while permitting yielding of said latter contacts.

9. The combination with a plurality of members each carrying a plurality of contacts, the contacts on one of said members having convex portions and the contacts on the other of said members being relatively wider and having concave portions for engagement therewith, an insulating member having substantially V-shaped passages extending therethrough, the contacts on said first mentioned member being located adjacent the points of convergence of the walls of said passages respectively, said wider contacts being admissible into said passages only at points substantially in line with or beyond the convex surfaces of said first mentioned contacts.

10. In a connector for electrical conductors, the combination with a receptacle comprising separable parts and provided with a single member shaped to form a contact

and to also form an offset lug to releasably secure said receptacle parts together, said member being also formed intermediate said contact and lug to provide a mounting for a terminal, and an attachment plug having a contact adapted to enter said receptacle for co-operation with the contact thereof.

11. A receptacle for cord connectors and the like comprising separable insulating members, one of said members having a pair of internally screw threaded inserts formed therein, conductive members riveted to said

latter mentioned insulating member by said inserts respectively, each of said conductive members having a portion formed to provide a contact and another portion formed to provide a lug, means co-operating with said lugs for releasably securing said insulating members together, and terminal screws carried by said inserts.

In witness whereof, I have hereunto subscribed my name.

GEORGE J. MEUER.
